UNITED STATES PATENT OFFICE.

ROBERT W. A. BREWER, OF PHILADELPHIA, PENNSYLVANIA, ASSIGNOR TO K. C. ACTON, OF BRYN ATHYN, PENNSYLVANIA.

VALVE MECHANISM FOR INTERNAL-COMBUSTION ENGINES.

Application filed November 21, 1924. Serial No. 751,242.

This invention particularly relates to a method of construction of a light slide valve, and particularly to a method of connecting the same to its operating mechanism so that 5 the operating attachment is removed from direct contact with the flame in the combustion chamber of an internal combustion engine.

The main object of this invention is to 10 provide a method of attachment and control in combination with valve mechanism described in United States Patents 1,292,783 and 1,439,894, and it is equally applicable to both types of split cuff valves described 15 therein.

Another object of this invention is to provide a sealing means for a segmental valve which passes through an annulus communicating with the combustion chamber in the 20 engine, and to provide suitable stops so that the pressure within the combustion chamber is resisted by these stops rather than by the actuating mechanism, which stops further aid in locating the valve itself in the means 25 provided for retaining the same in position.

Another object of my invention is to locate a sleeve valve particularly of the split cuff type within its containing annulus so that it may be easily and accurately assembled therein, irrespective of small mechanical errors in the machining of the containing 30 parts.

Another object of my invention is to provide a construction which is simple and cheap to manufacture, and which does not depend for its satisfactory performance 35 upon accurate tolerances and clearances.

Another object of my invention is to dispose the segmental valve within its containing 40 means so that a minimum surface of the valve is exposed to the temperature of the flame, and a maximum of the surface is in contact with heat conducting media, for example, water cooled passages.

Another object of my invention is to provide a construction which permits the operation 45 of the valve to be carried out by conventional mechanism for example, push rods and rocker arms, or an overhead cam shaft directly or indirectly operating the valve from the faces of the cams themselves.

A further object of my invention is to reduce the number of springs required when 50 this type of mechanism is actuated by a uni-directional cam and by disposing a sin-

gle spring in the manner shown, any number of radially placed reciprocating mechanisms can be operated, provided that they do not synchronize in their movements in a conflicting manner. 60

Another object of my invention is to provide a combustion chamber of approximately spherical shape having absence of local areas which can become unduly heated. By provision of such a form it is possible to 65 operate at pressures considerably higher than those in common practice with a resulting increase in power output from the same sized engine cylinders. 70

Some of the methods by which these various objects are obtained are known in connection with different constructions, but in the known forms have defects, particularly identified with possibilities of the collection 75 of solid deposits, and with the presentation of masses of metal to flame action. 75

Further, known and described methods of operating such valves involve expensive and special processes or those requiring very careful adjustment. 80

The described construction is suitable for application to any existing type of internal combustion engine which has a detachable head, and comprises principally the provision of a replacement head characterized by a water-cooled covering containing cylindrical openings, provided with suitable cylindrical stoppers or closure members so disposed in the complete assembly as to provide an annular space between cylindrical openings and closure members in which the described segmental valves are disposed. 85 90

For the purpose of illustrating my invention, I have shown in the accompanying drawings forms thereof which are at present preferred by me, since they will be found in practice to give satisfactory and reliable results, although it is to be understood that the various instrumentalities of which my invention consists can be variously arranged and organized and that my invention is not limited to the precise arrangement and organization of these instrumentalities as herein shown and described. 95 100

Figure 1 represents a vertical sectional view of a valve mechanism for internal combustion engines embodying my invention, certain of the parts being shown in elevation. 105

Figure 2 represents a horizontal section of 110

Figure 1, the section being taken on line 2-2 of Figure 1, the parts at the left of Figure 2 being shown in plan.

Figure 3 represents a vertical sectional view of another embodiment of my invention.

Figure 4 represents a perspective view of the left hand segmental valve seen in Figures 1 and 2 in detached position.

Similar numerals of reference indicate corresponding parts.

Referring now to the drawings, Figure 1 shows one application of this invention in which 1 represents a cylinder head; 2 represents a segmental port in the same, for the admission of explosive mixture. 3 is the exhaust port, and 4 is the closing member or plug. Between it and the cylinder head is an annular space 5; situated in this space is the segmental valve 6, operative with regard to inlet port 2 and the segmental valve 7, operative with regard to exhaust port 3. These valves are preferably retained within the annular space 5 by the packing rings 8, and are extended beyond these rings into the spring chamber 9 which encloses the spring 10. The extensions of the segmental valves are in this space attached to operating rods 11, preferably through the medium of shoe pieces 12, welded or otherwise firmly fixed to the extensions of the valves. The operating rods 11 are mounted in suitable eccentric bushes 13, freely placed in suitable bosses in the cover plate 14, which eccentric bushes can be adjusted after removal of the parts by a slight rotational movement such as described in U. S. Patent No. 1,292,783, to wit: a grub screw passing through the boss or a locking washer or plate engaging with serrations or flats and the extended part of the bush 13, which methods are used in common practice, so that the reciprocating parts herein described are properly in line, and have freedom of motion. The said eccentric bushes can then be locked in position by any known convenient means. The hole in the bush 13 through which passes the stem 11, is not concentric with the outside part of the bush 13 which fits into the boss of the cover plate 14. It will be obvious that in such a construction any rotation of the bush 13 in its containing boss will shift the center of the hole in the bush relatively to the center of the hole in the containing boss and thus the valve or cover plate 6 or 7 can be adjusted with regard to the containing parts, to wit: the closure plug 4 and the bore of the cylinder head 1.

In the arrangement shown a single coil spring 10 is so disposed that it is operative on the two reciprocating mechanisms and it will be clearly understood that the two operating mechanisms comprising the segmental valves 6 and 7 can be actuated in unison and control inlet and exhaust ports suitably

disposed for example, in two rings, or the said valves can be operated independently so that one actuates inlet port and the other actuates the exhaust port. The spring 10 is of relatively large diameter and is enclosed in chamber 9 between the cylinder head closure plug 4 and the cover plate 14 and is arranged to press against the underside of the extension 12 of valve stems 11. The depression of one stem 11, by its actuating mechanism, causes one side of the spring 10 to be depressed and does not depress the whole spring because the spring is of large mean diameter and the movement is small. By this arrangement and because of the material of which the spring is composed, a large total of spring steel of the desired flexibility can be placed in a small space and serves a double duty since each diametrically opposite portion of the spring is unaffected by slight movement of the portion of the spring at the opposite end of the diameter.

Referring particularly to the separate and independent movement of the two shoes, Figure 1 shows an annular projection or ridge 15, resting upon the rim of the closure head or plug 4 in such a manner that an effective seal is made preventing the escape of gases at the time of ignition and during the greater part of the working stroke.

The mechanism being preferably cam operated, the sleeve is in the position shown during this period. The ridge 15 also suffices to react against the pressure within the combustion chamber tending to force the segmental valves outwards through the annular space and the presence of the ridge in this position relieves the actuating mechanism of pressure, which would come upon it otherwise. The ridge 15 may abut against the circumferential termination of the closure plug 4 in the position shown in the drawing when the maximum pressure exists in the combustion chamber. This pressure tends to force the valves 6 and 7 out of the annulus and the function of the ridge 15, is to prevent this occurring and to provide a contacting surface to form a pressure seal. This contacting surface is subsidiary to the sealing means, for example the rings 8 shown on the drawing, and is shaped so as to force the closure plates or valves 6 and 7 outwards towards their containing walls.

Figure 3 shows a modified construction of valve mechanism in which an increased amount of protection is given to the valve by enclosing the lower part of it with an additional water-cooled wall. This construction also provides a constriction 21 between the combustion chamber and the working part of the cylinder, the object of the said constriction being to increase the amount of turbulence of the working fluid upon the compression stroke of the engine just prior to the timing of the ignition. The constriction 130

21 shown in Figure 3 has desirable features, particularly with regard to this type of valve mechanism and port arrangement, as previous practice has shown that sufficient 5 turbulence does not always exist for the best efficiency of combustion, particularly at low engine speeds.

10 The position of the spark plug can preferably be as shown in Figure 1 and this, combined with a suitable piston head form 17, provides a desirable shape of combustion chamber for permitting high compression pressures to be used. Water spaces are indicated at 18, inlet passages at 19, and exhaust 15 passages at 20.

Having thus described my invention what I claim as new and desire to secure by Letters Patent, is:—

1. In an internal combustion engine a power cylinder, a cylinder head, segmental inlet and outlet ports, a sectional sleeve valve reciprocable within the said cylinder head to control the opening of said ports, said sleeve being provided with a circumferential ridge on its inner face juxtaposed to the outer edge of the enclosed cylinder head member and operative with respect thereto, when the ports are closed by the said sleeve.

2. In an internal combustion engine, a power cylinder having fluid passages opening in two segmental ports within the said cylinder at the head thereof, a valve containing annulus, segmental valves adapted to cover said ports, an annular passage between the cylinder head closing member and the water-jacket of the cylinder containing said segmental valves an extension of each of said valves passing through the annulus and providing an operating means, a single spring in said cylinder for the return motion of both valve operating means, and suitable mechanism to impart reciprocating motion to each extension independently.

3. In an internal combustion engine including a power cylinder, having segmental inlet and exhaust ports in the cylinder head, two segmental sleeves mounted in an annular chamber adjacent to the combustion chamber and reciprocable therein, and controlling the opening and closing of said ports, means for sealing the annulus when the sleeves are stationary during the combustion stroke of the engine and means for actuating the segmental sleeves and a single spring in said cylinder for the return motion of both valve operating means.

4. In an internal combustion engine, a cylinder having a cylinder head, segmental inlet and exhaust ports in the cylinder head, two segmental sleeves mounted in an annular chamber adjacent to the combustion chamber, said sleeves operating in a similar manner to each other and in different phase to each other and controlling the timing of the opening and closing of the inlet and ex-

haust ports respectively and means for operating the said sleeves and a single spring in said cylinder for the return motion of both valve operating means.

5. In an internal combustion engine having segmental ports for inlet and exhaust in the combustion chamber thereof, two segmental closure plates capable of independent reciprocating motion and mounted in an adjacent annulus so disposed with reference to said ports that openings in the said plates uncover the ports when the plates move towards the pistons, means for sealing the annulus circumferentially at the combustion chamber, when said ports are closed by the said plates and means for reciprocating said plates.

6. In a segmental sleeve valve mechanism, wherein two independently actuated cover plates are reciprocated with reference to segmental ports in the combustion chamber of an internal combustion engine cylinder, one spring so disposed in the cylinder head as to actuate two cover plates.

7. In an internal combustion engine, a power cylinder provided with segmental inlet and exhaust ports within said cylinder at the head thereof, a head closure plug, a sleeve valve adapted to control said ports, comprising a segment contained in an annulus between the cylinder head and the cylinder head closure plug and an extension of said annulus provided to contain that portion of the valve between said ports and the engine piston.

8. In an internal combustion engine, a cylinder, a combustion chamber, a cylinder head, a reciprocating slide valve in said combustion chamber operative in an axial direction with regard to segmental ports in said combustion chamber and an annulus supporting the edge of the valve remote from said cylinder head.

9. In an internal combustion engine, a cylinder, a combustion chamber, a cylinder head, a reciprocating slide valve in said combustion chamber operative in an axial direction with regard to segmental ports in said combustion chamber and an annulus supporting the edge of the valve remote from the said cylinder head, said annulus forming a local restriction in the diameter of said combustion chamber.

10. In an internal combustion engine, a cylinder, a combustion chamber, a cylinder head, a reciprocating slide valve in said combustion chamber operative in an axial direction with regard to segmental ports in said combustion chamber, an annulus supporting the edge of the valve remote from said cylinder head, said annulus forming a local restriction in the diameter of the combustion chamber and a water jacket connecting with the water jackets around the cylinders.
